UNITED STATES PATENT OFFICE.

MICHAEL J. MILMOE, OF CHICAGO, ILLINOIS, ASSIGNOR TO F. B. REDINGTON COMPANY, OF CHICAGO, ILLINOIS, A CORPORATION OF ILLINOIS.

CARTON-FILLING MECHANISM.

1,425,997.

Specification of Letters Patent. Patented Aug. 15, 1922.

Application filed January 15, 1920. Serial No. 351,650.

To all whom it may concern:

Be it known that I, MICHAEL J. MILMOE, a citizen of the United States, residing at Chicago, in the county of Cook and State 5 of Illinois, have invented certain new and useful Improvements in Carton-Filling Mechanism, of which the following is a specification.

This invention relates to a checking device to be used in connection with the carton filling mechanism and has for its object the provision of such a device which shall be of improved construction and operation.

The invention is exemplified in the combination and arrangement of parts shown in the accompanying drawings and described in the following specification, and it is more particularly pointed out in the appended claims.

20 In the drawings—

Fig. 1 is a top plan view of a portion of a carton filling machine showing one embodiment of the present invention applied thereto;

25 Fig. 2 is a side elevation of the mechanism shown in Fig. 1;

Fig. 3 is a view similar to Fig. 2 but shows the mechanism at a different phase in its operation from that shown in Fig. 2;

30 Fig. 4 is a view looking from the left in Fig. 3; and

Fig. 5 is a section on line 5—5 of Fig. 2.

Where packages and cartons are filled by automatic machinery it is desirable to have 35 some means of checking each package to make sure that it has been properly filled as it would obviously be detrimental to the business to permit empty cartons to go to the trade along with those that are properly 40 filled. By the operation of the present invention each package is individually tested and those which have not been properly filled are automatically discarded.

The invention is shown in connection with 45 an automatic carton filling machine similar to that disclosed in my Patent No. 1,177,719 dated April 4, 1916, but it will be understood that the invention may be used in connection with a large variety of machines.

In the drawings there have been illustrated 50 only enough of the filling machine to show its relation with the testing mechanism, but the operation of the filling and closing mechanism may be understood by reference to the prior patent referred to above. 55

As shown in Figs. 2 and 3, folded cartons 10 are contained in a hopper 11 from which they are extracted by a finger 12, Fig. 1, which finger moves the cartons into filling position and at the same time opens the cartons to receive articles 13 which are moved into the open ends of the cartons by a plunger 14. The cartons are then moved forwardly along a platform 15 by a reciprocating member 16 and during their forward 60 movement the end flaps are closed by folders 17 and secured in place by tuckers 18. The operation of the parts thus far referred to 65 is described in detail in my patent referred to above. 70

A drive shaft 19 for the carton filling mechanism carries a cam disc 20 which engages a roller 21 on an arm 22 pivotally mounted at 23 and connected with an upright arm 24 to form a bell crank lever. A 75 link 25 is pivoted at 26 to the upper end of the arm 24 and is also pivotally connected at 27 to a rocker 28 pivotally mounted at 29 upon a block 30 secured to the machine frame. A bar 31 is also mounted on the 80 pivot pin 29 and is provided at its opposite end with an off-set finger 32 arranged to move vertically through a notch 33 in the table top 15 so that when the finger moves upwardly through the notch it will strike 85 one end of a carton resting upon the table top. A coil spring 34 connects the bar 31 and the end of the link 25 and normally tends to draw the finger 32 upwardly through the notch 33. A pin 35 on the 90 rocker 28 engages the upper edge of the bar 31 and forces the bar downwardly through the notch 33 when the rocker 28 is moved forwardly by the arm 24. A catch 36 is pivoted at 37 on a bracket plate 38 extending 95 downwardly from the table 15 and a spring 39 automatically moves the catch 36 in position to engage the upper edge of the finger

32 when it is moved to its lowermost position by the oscillation of the arm 24. The catch 36 is provided with a beveled upper face 40 so that the catch will move backwardly to permit the finger 32 to pass when the bar 31 is forced to its lowermost position. A pin 41 is provided on the plate 38 to limit the movement of the catch 36.

A rocker plate 42 is pivoted at 43 on the bracket 38 and is pivotally connected at 44 with a link 45 which has its opposite ends slotted at 46 to receive a pin 47 on the arm 24. A link 48 is pivoted at 49 to the plate 42 and has its opposite end pivoted at 50 to an arm 51 secured to a rock shaft 52. The rock shaft 52 is provided with rocker arms 53, the upper ends of which are normally positioned in notches 54 in the table 15 just in front of the notch 33, as shown in Fig. 1. The rock shaft 52 is journaled in a bearing bracket 55 secured to the under face of the table 15. A link 56 is pivotally connected at 57 to the upper end of the catch 36 and the opposite end of the link 56 is provided with a slot 58 through which the pivot pin 44 on the rocker plate 42 projects. The slot 58 is elongated to extend in both directions from the pin 44.

The operation of the mechanism is as follows:

The filled cartons 10 are moved along the upper surface of the table 15 by the feeding device for the filling mechanism and at the same time the arm 24 is reciprocated about its pivot 23 by the rotation of the cam 20. In Fig. 2 the arm 24 is shown at the extreme left of its reciprocating movement and as it moves to the right from that position the first effect is to impart tension to the spring 34 by the upward movement of the link 25 due to the rotation of the rocker 28 about its pivot 24. When the pin 47 reaches the end of the slot 46 in the link 45 the rocker plate 42 will begin to move to the right, as viewed in Fig. 2, and this in turn will cause the arms 53 to move upwardly and forwardly through the notches 54 so that the upper ends of the arms engage one of the cartons 50 on the table 15 and slide all of the cartons in front of the one engaged forwardly along the table, as shown in Fig. 3, so that they are spaced away from the carton immediately above the opening 33. This will 55 free the carton above the opening 33 from lateral pressure.

As the link 45 is drawn farther to the right in Fig. 2 the pin 44 in the rocker plate 42 will engage the end of the slot 58 in the link 56 and as the arm 24 reaches its extreme position the catch 36 will be drawn backwardly by the link 56 until it disengages the finger 32, thus freeing the bar 31 and permitting it to move upwardly 65 under the influence of the spring 34. The

upward movement of the bar 31 will cause the finger 32 to strike the carton immediately above the notch 33 in the table top 15. The tension of the spring 34 is so regulated that if the carton is empty the force of the blow delivered by the finger 32 will flip the carton from the table in the manner shown in Figs. 3 and 4. The fact that the cartons in front of the one struck have been moved forwardly by the arm 53 leaves the carton free to move under the influence of the blow delivered to its lower face. If the carton has been properly filled the weight of the article which it contains will be sufficient to prevent dislodgement of the carton. The inertia of the article within the carton assists in overcoming the impact of the blow which has gained momentum due to the movement of the bar 31 and finger 32. After this momentum has been overcome by the inertia of the article in the carton the weight of the article is sufficient to prevent dislodgement of the carton by the tension of the spring 34. As the arm 24 begins to move to the left the pin 35 on the rocker 28 will again force the bar 31 and the finger 32 to their retracted position. After the pin 47 has moved the length of the slot 46 the link 45 will move the rocker plate 42 to retract the rocker arm 53 to a position beneath the upper surface of the table 15. This will leave the upper surface of the table free from any obstruction so that the next forward movement of the cartons 10 100 will bring another carton into position above the finger 32. The slot 58 in the link 56 will permit the catch 36 to spring backwardly as the finger 32 moves over the inclined face 40 into position to be held by the nose of the catch. The mechanism is all timed to operate in unison with the filling machine so that each carton as it moves over the notch 33 in the table top receives a blow on its lower face at one end and any 110 empty carton is thus automatically separated. The empty carton is thus automatically separated

I claim:

1. In combination, means for supporting a series of containers, and means for imparting sufficient force to each container in said series to discharge said container from said support in case said container is not properly filled.

2. In combination, means for supporting containers, means for moving a series of containers over said support, and means for delivering a blow to each of said containers of sufficient force to displace a container which has not been properly filled but not 125 to displace a container which is properly filled.

3. The combination with means for filling containers, of means for delivering a blow to each of said containers after it has been 130

submitted to said filling means to ascertain whether or not said container has been properly filled.

4. The combination with automatic means 5 for filling and closing containers, of means for delivering a blow to each of said containers after it has passed said filling and closing means, and a resilient device for actuating said blow delivering means.

10 5. The combination with a support for a container, and resilient means for exerting a force for displacing said container from said support, the strength of said resilient means being sufficient to displace a 15 container that has not been properly filled but insufficient to overcome the weight of a filled container.

6. The combination with a support for 20 containers, of a device for delivering a blow to a container on said support, and resilient means for moving said device a distance prior to the engagement of said container by said device to permit said device to gain momentum prior to striking 25 said container.

7. In combination, a support for containers, a device for delivering a blow to a container on said support, and resilient means for moving said device through an appreciable 30 distance prior to the delivery of said blow to permit said device to gain momentum to assist in displacing said container if empty but which will be overcome by the inertia of the contents of said container if 35 said container is properly filled.

8. The combination with a support for a container, and resilient means for delivering a blow to the lower face of said container to displace said container on said support 40 if said container is not properly filled.

9. The combination with a support having an opening therein, a tapper movable upwardly through said opening, and a spring for moving said tapper through said 45 opening to cause said tapper to strike the lower face of a container on said support above said opening.

10. The combination with a support for 50 containers, of a tapper for delivering a blow to a container on said support, resilient means for actuating said tapper, a catch for holding said tapper at a distance from a container on said support, and means for releasing said catch to permit said tapper 55 to strike said container under the influence of said resilient means.

11. The combination with a support, of 60 means for moving containers over said support, a tapper for engaging said containers, a spring for actuating said tapper, and mechanism for tensioning and releasing said spring to cause said tapper to deliver a blow to a container on said support.

12. The combination with a support, of 65 means for moving a series of containers

along said support, a tapper arranged to deliver a blow to each of said containers moved along said support, a spring for actuating said tapper, and mechanism for moving said tapper to place said spring under tension 70 and for subsequently releasing said tapper to permit said tapper to deliver a blow upon a container of sufficient force to displace said container if said container is not properly filled. 75

13. The combination with a support, of means for moving a series of containers along said support, means for separating said containers at one position in said series to relieve one of said containers from pressure due to engagement with another container of said series, and means for delivering a blow to the container thus relieved. 80

14. The combination with a support, of means for moving a series of containers 85 along said support, means for separating containers at one point in said series, and means for exerting force upon a container adjacent the point of separation to displace said container if said container is not properly filled. 90

15. The combination with a support, of means for moving a series of containers along said support, means for relieving each container in said series from pressure due 95 to contact with other containers in said series, and means for imparting force to said container while so relieved to displace said container in case it is not properly filled. 100

16. The combination with a supporting platform, of means for moving a series of containers along said platform, a contact member arranged to move into engagement with a container on said platform to force said container out of engagement with the container next adjacent thereto, and a tapper for striking said adjacent container when thus relieved. 105

17. The combination with a platform, of means for moving a series of containers along said platform, a contact member arranged to move upwardly from beneath said platform into engagement with the lateral face of a container thereon to force said container out of engagement with the container next adjacent thereto, a tapper movable upwardly from beneath said platform to strike the container thus relieved, and resilient means for actuating said tapper. 110 115

18. The combination with a platform for supporting containers, of means for engaging a container on said platform adjacent one end of said container to displace said container from said platform in case the 120 weight of the contents of said container is insufficient to overcome the force of said engaging means.

19. The combination with a platform having one edge thereof unobstructed, means

for moving containers along said platform, and a tapper arranged to strike the lower face of a container on said platform adjacent one end of said container to displace 5 said container from said platform in case the weight of the contents of said container is insufficient to overcome the force of said tapper.

20. The combination with a platform, of 10 means for moving a series of containers along said platform, means for separating said containers in said series at one point therein, and resilient means for delivering a blow to a container adjacent the point of 15 separation in said series to displace said container from said platform in case the contents of said container is insufficient to overcome the force of the blow delivered by said resilient means.

21. The combination with a platform, of 20 means for moving a series of containers along said platform, means for separating the containers of said series at one point, and a tapper arranged to deliver a blow to 25 one end of a container adjacent the point of separation of said series to flip said container from said platform in case the weight of the contents of said container is insufficient to overcome the force of said blow.

22. The combination with a support for a 30 container, of a movable member for engaging a container on said support, means for holding said member out of contact with said container, resilient means for exerting 35 tension on said member, and means for releasing said holding means to permit said member to strike said container.

23. The combination with a platform, of 40 means for moving a series of containers along said platform, and a resilient device arranged to operate in timed relation with said moving means to deliver a blow to each of said containers moved along said platform.

24. In combination, a platform, means for 45 moving a series of containers along said platform, a pivoted member arranged to move into engagement with a container at one position on said platform, resilient 50 means for actuating said pivoted member, a catch for holding said pivoted member in retracted position against the tension of said resilient means, means for releasing said catch to permit said member to move 55 under the influence of said resilient means into contact with said container on said platform, and means for restoring said pivoted member to its retracted position prior to the subsequent movement of another container into position to be engaged by said pivoted member.

25. The combination with a platform, of 60 means for moving a series of containers along said platform, a pivoted arm having 65 means thereon for engaging a container at

one position on said platform, a catch for holding said arm in retracted position, a spring for drawing said arm into engagement with a container on said platform, a rocker for exerting tension on said spring, 70 means for actuating said rocker to place said spring under tension, means for subsequently releasing said catch to permit said arm to move under the tension of said spring into engagement with a container on 75 said platform, and means on said rocker for restoring said arm to retracted position subsequent to the release of said catch, and means for automatically actuating said catch to cause said catch to retain said arm in 80 said position.

26. The combination with a support, of 85 means for moving containers along said support, a movable device for striking each container as it passes a given position on said support, and means for separating other containers in said series from each container while it is in position to be struck.

27. In combination, a support, means for moving a series of containers along said 90 support, resilient means for delivering a blow to each container of said series while it is in a given position on said support, means for separating containers in said series from each container while in position 95 to be struck by said resilient means, a catch for retaining said resilient means in retracted position, and mechanism for releasing said catch subsequent to the operation of said separating means. 100

28. The combination with a support, of 105 means for moving a series of containers along said support, a tapper for striking each container in said series when at a given position on said support, a catch for holding said tapper in retracted position, a contact member for engaging a container for separating the containers of said series from the one in position to be struck by said tapper, actuating means for operating said contact member and for releasing said catch, and lost motion mechanism between said actuating means and said catch to cause said contact member and catch to operate successively so that said tapper will strike 110 said container subsequent to the operation of said contact member.

29. The combination with a support, of 115 means for moving a series of containers along said support, a pivoted tapper arranged to strike each container as it moves into a given position on said support, a spring for actuating said tapper, a catch for holding said tapper in retracted position against the tension of said spring, a reciprocating member, means actuated by said reciprocating member for exerting tension on said spring, lost motion mechanism connecting said reciprocating member with said catch to release said catch subsequent to the 120 125 130

tensioning of said spring, a contact member for separating the cartons in said series, mechanism actuated by said reciprocating member for operating said contact member prior to the release of said catch, means for restoring said tapper to its retracted position, and a spring for automatically moving said catch into engagement with said

tapper to retain said tapper in retracted position while a second container is moved into 10 position to be engaged thereby.

In testimony whereof I have signed my name to this specification on this 10 day of January, A. D. 1920.

MICHAEL J. MILMOE.
